UNITED STATES PATENT OFFICE.

JESSE ALEXANDER, OF NEW YORK, N. Y., ASSIGNOR OF ONE-HALF TO HUDSON BIDWELL, OF NEW YORK, N. Y.

TYPE-WRITER ACTION.

1,041,556.

Specification of Letters Patent.

Patented Oct. 15, 1912.

Application filed June 22, 1911. Serial No. 634,705.

To all whom it may concern:

Be it known that I, JESSE ALEXANDER, a citizen of the United States, and resident of New York, in the county of Kings and State 5 of New York, have invented certain new and useful Improvements in Type-Writer Actions, of which the following is a specification.

My invention relates particularly to a key 10 and type bar mechanism for a front stroke visible writing machine.

The object is to provide a light but strong and durable construction in which the touch is very light and yet in which great pressure 15 may be exerted when desired for manifolding etc.

Another object is to secure rapidity of action.

The details of the invention are illustrated 20 in the accompanying two sheets of drawings.

Figure 1 is a vertical section of a machine showing a side view of one unit of a key and type bar mechanism embodying the improvements of my invention showing the parts in 25 the position of rest. Fig. 2, is a perspective view of parts of the type bar mechanism separated. Fig. 3, is a view similar to Fig. 1 showing the parts in the printing position.

The key levers such as 1 are all pivoted at 30 the rear of the machine as for instance, on pivots such as 2 carried by the frame 3. Each key lever has an upwardly projecting finger 4 under tension of a spring 5. The latter is secured to the end of a screw 6 which 35 is adjustable in the frame of the machine for varying the tension. The key lever carries a stud or suitable projection 7 for engaging the intermediate lever which will be herein-after described.

40 The type bars such as 10 are all pivoted for instance, as at 11 in the type bar plate 12. The type itself 13 has a shank 14 which fits in a socket 15 on the end of the type bar. The rear end of the type bar has an arm 16 45 carrying the roller 17. The type bar has a lug 18 for the pivot 11 and a lug 19 for connecting to the intermediate lever 20.

The intermediate lever 20 is pivoted at 21 and has a forwardly projecting arm 22 with 50 a slot 23 to engage the stud 7 on the key lever. The upper end of the lever 20 has an arm 24 with a curved bearing surface 25

adapted to coöperate with the roller 17 to start the type bar in its upward movement. The intermediate lever also has an arm 26 55 with a slot 27. The link 28 carries a pin 29 which fits in the slot 27. The link 28 is pivotally connected to the lug 19 of the type bar by the pin 30.

When the key lever 1 is depressed the connection between the stud 7 and arm 22 causes the intermediate lever 20 to be rocked on its pivot 21. The arm 24 moving forwardly presses the roller 17 and arm 16 of the type bar downward and forward and 60 thus raises the type 13 to the printing position, the roller 17 rolling along the curved surface 25 of the arm 24. Near the latter part of the movement of the type bar 10 the pin 29 carried by the link 28 is forcibly engaged by the wall of the slot 27 in the arm 26 and direct pressure is brought to bear in a toggle-like manner to press the type 65 against the platen 31. In Fig. 3 it will be noted that in the printing position the pivot 70 21, arm 26, pin 29, link 28 and pivot pin 30 are very nearly in a straight line with the type bar 10. This enables me to secure a great amount of pressure for manifolding 75 and similar purposes. As soon as the key 80 lever is released a short distance, the type bar is free to fall back to its normal position of rest. A stop 32 may be provided on the face of the plate 12 to limit the stroke of the type bar if desired.

The carriage construction is not illustrated herein but may include a toothed rack such as 33 to coöperate with an escapement dog 34 pivoted at 35. This dog has the depending arm 36 connected at its lower end 90 to a universal frame 37 having a universal bar 38 for engagement by the shoulders such as 39 on the intermediate levers. In this manner the control of the carriage and ribbon mechanism is effected through the medium of the intermediate levers.

In the form shown I have illustrated a ribbon guide 40 connected to a bell crank lever 41 pivoted at 42. One arm of this lever is connected by link 43 to the arm 36.

The arm 36 may be under the tension of a spring 44 and in this manner resistance is offered to the movement of the intermediate levers and a force is provided for assisting

in returning the intermediate lever and attached parts to their normal position of rest when released.

What I claim is:—

- 5 1. In a key and type bar mechanism, a pivoted key lever, a pivoted type bar, a pivoted intermediate lever connected to said key lever, a link connecting said intermediate lever and said type bar, said type bar and said intermediate lever each having a projecting arm in rear of said link, said arms being adapted to coöperate with each other through a part of their movement.
- 10 12. In a key and type bar mechanism, a pivoted type bar having a downwardly and rearwardly projecting arm and a lug located between the end of said arm and the printing end of said type bar beneath the type bar pivot, a lever having an arm for coöoperating with said type bar arm through a part of its movement and a link connecting said lever and said lug on said type bar.
- 15 15. In a type bar action, a type bar, a pivot therefor, a roller carried by said type bar, a pivoted lever having an arm for engaging said roller and a link connecting said arm and said type bar.
- 20 20. In a type bar action, a type bar, a pivot therefor, a roller carried by said type bar, a pivoted lever having an arm for engaging said roller and a link connecting said arm and said type bar beneath the type bar pivot.
- 25 25. In a type bar action, a type bar, a pivot therefor, a roller carried by said type bar, a pivoted lever having an arm for engaging said roller and a link connecting said arm and said type bar.
- 30 30. In a type bar action, a type bar, a pivot therefor, a roller carried by said type bar, a pivoted lever having an arm for engaging said roller and a link connecting said arm and said type bar beneath the type bar pivot.
- 35 35. In a type bar action, a type bar, a pivot therefor, a roller carried by said type bar, a pivoted lever having an arm for engaging

said roller and a link connecting said arm and said type bar beneath said pivot and between said roller and the printing end of said type bar.

40 6. In a type bar mechanism, a pivoted type bar having a downwardly and rearwardly projecting arm, a lever having an arm for engaging said type bar arm and a second arm in front thereof and a link connecting said second arm and said type bar.

45 7. In a type bar mechanism, a pivoted type bar having a downwardly and rearwardly projecting arm, a lever having an arm for engaging said type bar arm and a second arm in front thereof and a link connecting said second arm and said type bar beneath its pivot.

50 8. In a type bar mechanism, a pivoted type bar having a projecting arm, a lever having an arm for engaging said projecting arm and a second arm having an elongated slot and a link pivotally connected to said type bar and having a pin engaging in said slot.

55 9. In a type bar mechanism, a pivoted type bar having a projecting arm, a lever having an arm for engaging said projecting arm and a second arm having an elongated slot, a link pivotally connected to said type bar and having a pin engaging in said slot, and a key lever for operating said parts.

60 JESSE ALEXANDER.
